UNITED STATES PATENT OFFICE.

WILLIAM B. TURNER, OF NEW YORK, N. Y.

MOMENTUM CAR-BRAKE.

SPECIFICATION forming part of Letters Patent No. 268,755, dated December 5, 1882.

Application filed June 28, 1882. (No model.)

To all whom it may concern:

Be it known that I, WILLIAM B. TURNER, a citizen of the United States of North America, and a resident of the city, county, and State of 5 New York, have invented a new and useful Improvement in Momentum Car-brakes, of which the following is a specification.

This invention relates to mechanism adapted to effect the application of car-brakes by means 10 of the draw-bar or its equivalent; and its object is to provide a brake that will operate with the cars running in either direction and at any rate of speed, and by the extension as well as the compression of the draw-bar.

15 The invention consists of an arrangement of levers, movable fulcra, and other devices connected with the draw-bar and brake-beams, so that they may be operated by the movements of said bar in either direction to apply the 20 brake-shoes to the wheels, which levers, fulcra, and other devices are so constructed and arranged that the movement of the brake-beams toward the wheels is utilized to disengage the 25 brake when the car is standing still and to apply the brake when the car is moving, all of which will be hereinafter fully described.

Figure 1 is an enlarged view of certain details of the brake mechanism. Fig. 2 is a sectional side elevation of a car-truck, showing 30 the brake mechanism partly in section. Fig. 3 is a sectional side elevation of a car-truck, showing the brake mechanism partly in section from the opposite side. Fig. 4 is an end elevation of a car-truck, showing the brake 35 mechanism in section on line $x-x$, Fig. 2. Fig. 5 is a plan of the reverse of certain parts of the brake mechanism applied to a car-truck. Fig. 6 is an enlarged side elevation of the chain-carrier.

40 Similar letters of reference indicate corresponding parts.

Secured on the inner end of the draw-head, A, is a transverse lever, A', one end of which is pivoted at α on the car-frame, while the other 45 end is free to move in the guide A², which is also secured on the car-frame.

In a fixed guide-block, B, is the vertically-movable channelled block B', containing a sliding chain-carrier block, B², provided on its lower side with a rectangular tooth or cog, b, with which at times in the operation of the brake

the free end of the lever A' is designed to come in contact. This channelled block B' is held in place within the guide B by means of a bell-crank, C, which is connected with its top by rod g', and is pivoted in a fixed block, C². One arm of the bell-crank C is connected by rod C' to the upper end of a lever, D, in whose lower forked end is fixed a stop or fulcrum, e, which is part of said lever, as clearly shown in Fig. 1.

To the opposite ends of the carrier-block or chain-carrier B² are secured the opposite ends of the chain B³, whose bight is secured to the extremity of the long arm of the forward brake-lever, E, and as said chain B³ passes over a sheave, d, it is evident that the end of the lever E to which said chain is attached will be pulled in one and the same direction by the horizontal movement of the carrier B², whether the latter be moved rearward or forward. The 65 brake-levers E E' are respectively pivoted in lugs f, that project from the brake-beams F F', on which are brake-shoes F², and their short arms are connected by a chain or rod, g, while the long arm of the lever E' is connected by a chain, g², to the brake-staff G, so that in order 70 to set the automatic brake correctly the hand-brake staff G may be wound up until the brake-shoes are applied to the wheels, and then may 75 be slackened off sufficiently to remove said shoes a short distance from the wheels.

A pitman, H, having one end attached to the forward brake-beam, F, extends rearward, and has pivoted on its free end an elbow-lever, 85 H', that is held upward against the suspension-block I by chains h, which pass over the arm K, that is rigidly attached to the car-frame. The rear end of this suspension-block I is held in position, so that it may be vertically moved, 90 by a clamp or staple, i, and a spring, i', while in the fork of the forward end of said block I is pivoted the segmental rocking fulcrum L, whose upper curved edge normally is held nearly in contact with the front car-axle, M. 95 A link, O, connects this rocking fulcrum L with the bell-crank lever P, that is pivoted in the front of the forked supporting-arm K, and has its forward end held movably in place by a spiral spring, k, while its rear trebly-toothed 100 end is entered between the prongs of the forked lever D.

A pitman, H^2 , parallel with and pivoted on the side of the pitman H , has connected with its inner end an upright lever, Q , that is fulcrumed on the arm K , and has its upper end 5 fixed to the lever D , near the top thereof.

Assuming the improved brake mechanism to be in position shown in Figs. 2 and 3, and that the car is being backed up for coupling, the engine pushing from the opposite end, or the 10 end opposite to that to which the brake mechanism is attached, it follows that the car-wheels will move before the draw-head moves, and that when the draw-head A makes contact with another draw-head the former will be pushed 15 in, and thereby push the lever A' in contact with the tooth or cog b of the chain-carrier B^2 and force the latter rearward, thereby causing the chain B^3 to move the brake-levers $E E'$, by which the brake-beams $F F'$ are advanced toward the car-wheels R , which motion of the 20 beams $F F'$ through the pitman H and elbow-lever H' raises the suspension-block I , whereby the rocking fulcrum L is brought in contact with the axle M as the latter revolves 25. The continued forward rotation of the axle M at once throws the fulcrum L off into the position shown in dotted lines, Figs. 2 and 3, and in assuming this position the said fulcrum L , through the medium of the link O , moves the 30 fulcrum-lever P , so that the central tooth, c^2 , of the latter is raised above the stop c of the lever D and no longer serves as a fulcrum for said lever D . At the same time the pitman H^2 , moving inward with the pitman H , operates the lever Q to advance the lower end of 35 the lever D and bring the stop c in contact with the lower tooth, c^3 , of the lever P , which tooth c^3 then becomes the fulcrum for the said lever D . At the same time, by the action of the 40 pitman H^2 and lever Q , the upper end of the lever D is carried forward and operates, through the medium of the rod C' , on the bell-crank C to cause the latter to raise the channeled block B' and the chain-carrier B^2 , so that the cog b 45 of the latter is lifted above the plane of motion of the lever A' , thereby permitting the farther rearward motion of said lever A' without engaging the brakes, and consequently permitting the further backing of the car without the 50 automatic application of the brakes. All this is accomplished before the brake-shoes come in contact with the car-wheels.

If an engine be backed up against that end of the car to which the break mechanism is 55 attached, it comes first in contact with the draw-head A , and, pushing the latter in, thereby forces the lever A' in contact with the cog b of the carrier B^2 and moves the latter rearward, which rearward motion of the carrier B^2 60 causes the chain B^3 to move the brake-levers $E E'$, by which the brake-beams $F F'$ are advanced toward the wheels, which motion of the brake-beams $F F'$, through the pitman H and elbow-lever H' , raises the suspension-block I , whereby the rocking fulcrum L is brought in contact with the axle M . The car,

however, being still stationary, the rocking fulcrum L remains also stationary, and by its link attachment O with the lever P causes the central tooth, c^2 , of the latter to be held in position against the stop c of the lever D , and to serve as a fulcrum therefor; and the farther rearward movement of the draw-head A causes the upper end of the lever D to move forward, and through the medium of the rod C' and crank C to raise the carrier B^2 so that its cog b is lifted above the plane of motion of the lever A' , thereby permitting the farther rearward motion of the said lever A' without engaging the brakes. When the car is in motion, whether 80 pushed or pulled by the engine, the slowing of the latter causes the compression or extension of the draw-bar A , as the case may be, whereby, as hereinbefore explained, the fulcrum L is pressed against the axle M . The rotation of 85 said axle M then at once throws off the said fulcrum L rearward or forward, as indicated in dotted lines, Fig. 2, which movement of the fulcrum L , transmitted through the link O , throws the lever P entirely free from the lever-stop c , as indicated in dotted lines, Fig. 1, so that the lower end of said lever D has no longer any fulcrum to work against, and consequently becomes inoperative for disengaging the brakes, for, being deprived of a fulcrum for its lower end, its upper end cannot be moved forward by the action of the lever Q , and hence cannot lift the carrier B^2 so that the cog b of the latter shall be on a higher plane than the lever A' . Hence the said carrier B^2 , being held down in its normal position by the springs o , that bear on the channeled block B' , presents its cog b to the lever A' as the latter is forced rearward or forward, as the case may be, and is thereby itself moved rearward or forward, causing the chain B^3 , through the medium of the levers $E E'$, to draw the brake-beams $F F'$ inward, and thereby apply 95 the shoes to the car-wheels. 100

From the above it will be understood that 105 the movements of the brake-beams toward the car-wheels, when the car is standing still, operate to disengage the brake or prevent its application, while the same movement of the 110 brake-beams, when the car is in motion, operates, through movable fulcra, to apply the 115 brakes. In other words, when the wheels are stationary the movement of the brake-beams toward them causes the rocking fulcrum L to operate as a fulcrum, and hold the lever P in 120 position to serve as a fulcrum for the lower end of the lever D , so that the carrier B^2 may be raised above the draw-bar lever A' and the 125 brake be disengaged or its application prevented; but when the wheels rotate the rocking fulcrum L is, by the approach of the 130 brake-beams toward the wheels, brought against the wheel-axle and thrown off by the rotation of said axle in such a position that it no longer acts as a fulcrum itself, and at the same time prevents the lever P from operating as a fulcrum for the brake-disengaging lever D . Hence 135

said lever D becomes inoperative, and the brakes can be set.

This improved device can be made to operate as a single-acting brake only and by compression of the draw-head by constructing the rear of the cog b on a slope or incline, as indicated by dotted lines at s, Fig. 6. In such case the extension of the draw-head would draw the draw-bar lever A' over and past the cog b without moving the chain-carrier and its attachments.

Having thus described my invention, I claim as new and desire to secure by Letters Patent—

1. In a momentum car-brake, the combination, with the brake-beam and wheel-axle, of suitable connecting-levers, and the movable fulcrum L and its operating mechanism, substantially as herein shown and described, whereby the movement of the brake-beam toward the wheels is made operative to disengage or prevent the application of the brake, as set forth.
2. In a car-brake, the combination, with the brake-beams and attached connected brake-levers and lever-operating chains, of a chain-carrier arranged to move horizontally, and a chain-carrier guide consisting of a channeled block having a vertical movement in a fixed guide-block, substantially as described.
3. In a car-brake, the combination, with the brake-beams provided with shoes and having attached connected brake-levers and lever-operating chain, of a chain-carrier reciprocating in a channeled guide-block adapted to be moved horizontally for applying the brakes and vertically to prevent the application or to release the brakes, substantially as herein shown and described.
4. In a car-brake, the combination, with a chain-carrier having a horizontal motion, a vertically-moving channeled guide-block, and its elevating and depressing mechanism supporting the chain that operates the brake-levers, of a draw-bar provided with a lever for moving said carrier, substantially as set forth.
5. In a car-brake, as a means for vertically moving the chain-carrier to prevent the application of the brake or to release the same, the combination, with the carrier and brake-beam,

substantially as herein shown and described, of pitmen H H², levers Q D, rods C' g', and bell-crank C, as set forth.

6. In a momentum car-brake, the combination, with the rocking fulcrum L, of the draw-head and lever A A', movable toothed chain-carrier B², chain B³, connected brake-levers E E', brake-beams F F', pitman H, elbow-lever H', and suspension-block I, substantially as herein shown and described, whereby said rocking fulcrum is brought in contact with the car-axle by the movement of the brake-beams toward the car-wheels, as set forth.

7. In a momentum car-brake, the combination, with the rocking fulcrum L, lever D, provided with stop c, and toothed lever P, of the link O, substantially as herein shown and described, whereby the lever P is moved so as to deprive the lever D of a fulcrum, as set forth.

8. In a car-brake, the combination, with the draw-bar, brake-beams, and their connected and connecting mechanisms, of two rocking or movable fulcrums linked together, substantially as herein shown and described, whereby the rotation of the car-axle operates, through suitable devices, to set the brake mechanism in operative condition, as set forth.

9. In a car-brake, the combination, with the lever and its attached mechanisms for raising and lowering the chain-carrier, of a movable fulcrum, substantially as herein shown and described, whereby said lever may be rendered operative or inoperative, as set forth.

10. In a momentum car-brake provided with a rocking fulcrum adapted to be thrown out of contact with the car-axle by the rotation thereof, the combination, with said fulcrum, of a supporting suspension-block and suitable devices for moving either end thereof vertically, substantially as herein shown and described.

In testimony that I claim the foregoing as my invention I have signed my name, in presence of two witnesses, this 24th day of June, 1882.

W. B. TURNER.
